UNITED STATES PATENT OFFICE.

ADAM M. SPAETH, OF WEST BEND, WISCONSIN.

BOX-WASHING APPARATUS.

Application filed July 15, 1922. Serial No. 575,422.

To all whom it may concern:

Be it known that I, ADAM M. SPAETH, a citizen of the United States, and resident of West Bend, in the county of Washington and State of Wisconsin, have invented certain new and useful Improvements in Box-Washing Apparatus; and I do hereby declare that the following is a full, clear, and exact description thereof.

10 My invention relates to washing apparatus and it especially refers to means for washing skeleton boxes or crates which are used as containers for bottles.

15 An object of my invention is to provide a simple type of washing machine which can be operated in any bottling works at a small cost, the device as a whole being capable of meeting the demands of both a small plant or a large plant, depending upon the length 20 of the unit.

25 Another object of my invention is to provide a washer, which is extremely cheap in its manufacture, to meet all demands, and which washer can be manipulated by a single operator.

With the above and other objects in view 30 my invention consists in certain peculiarities in construction and combination of parts, as will be hereinafter set forth and described with reference to the accompanying illustrations and subsequently claimed.

In the drawings:—

Figure 1 represents a plan view of a 35 washer embodying the features of my invention.

Figure 2 is a longitudinal sectional view of the same, the section being indicated by line 2—2 of Figure 1.

Figure 3 is a cross section of the machine, 40 the section being indicated by line 3—3 of Figure 2, and

Figure 4 is an end view of said machine, the same being taken looking toward the feed end of the device to particularly illustrate the fluid distributing pipe connections. 45

Referring by characters to the drawings, 1 represents a skeleton frame or bed, having longitudinal sills 2, upon which are mounted longitudinally disposed channel irons 3. The inner flanges of the channel irons 3 form guides for boxes or crates A, whereby the same are held against lateral play when they are manually fed through the washing machine; it being understood 50 that any conveyor mechanism for mechanically conveying such boxes can be utilized.

The boxes, in their travel, are supported by a group of transversely disposed rollers 5, which rollers are journaled in boxes 5', and are secured to the inner lower face of 60 the channel iron 3, it being observed that by this arrangement the journals and their boxes are encased or protected against moisture, due to the fact that the upper flanges of the channel irons project thereover and 65 form shedding surfaces.

Mounted upon the frame, directly under the rollers 5, are a series of longitudinally disposed spaced fluid pipes 6, which pipes are provided with upstanding discharge 70 nipples 6', and are preferably staggered with relation to each other, whereby an even distribution of fluid discharged from the group of pipes is had. The nozzles terminate upon a plane slightly below the upper 75 surface of the box guide rollers 5.

The frame 1 is provided with a metallic catch basin 7 in the form of an inverted cone, the bell mouth of which is disposed under the pipe series 6, whereby discharge 80 from said pipes will be collected and delivered to a conduit 7' at the bottom of the catch basin, and this conduit may lead to a sewer.

The group of fluid discharge pipes 6 are connected to one leg 8 of a looped mixing head, the opposite leg 8' of said head being connected by a branch fluid delivery pipe 9. This branch pipe 9 is in turn connected to a steam supply pipe 10 and a water supply 90 pipe 10', which pipes are positioned approximately parallel to a point near the mixing point and lead from a suitable source of supply. The pipes 10 and 10' have fixed thereto a bracket 11 carrying a detent 12, to which is pivoted an actuating lever 13. The lever 13 in turn is connected by a link 13' to arms 14—14' of valves 15—15', which control the fluid pipes, there being other cut-off valves 16—16' in said fluid pipes for permanently 95 checking or opening the supply of fluid to the system.

The cut-off valves 16—16' can be regulated to determine the proportions of steam and water to be ultimately mixed and discharged from the group of pipes 6. The valves 15—15' are set with relation to their actuating arms, whereby when said valves are moved a predetermined distance, a proper volume of water and steam is admitted to the mixing head through the pipe 9. Hence, it will be seen that when it is desired 100 105 110

2
to operate the machine, one or more boxes 5 13, may be manually slid upon the run-way, comprising the group of rollers, and the same operator can, by manipulating the lever in the desired quantities to the group of boxes to be cleansed or sterilized.

For example, in some cases, steam only 10 may be used, and in other cases, water can be mixed with the steam, or water can be used alone for rinsing purposes, the main problem solved being that the device as a whole is simple in construction and can be operated by anyone unskilled in the art of 15 mechanics.

I claim:—

1. A box washing apparatus comprising a bed, a grid of parallel water pipes carried thereby and having upright jet nozzles at 20 intervals, a loop-shaped header whereof one member is connected with said pipes and the second member is connected by pipes with the first, and regulable means for feeding water and steam to said second member; 25 combined with a box support comprising side bars located in a plane above said grid, and rollers connecting said bars and spaced above said nozzles.

2. A box washing apparatus comprising a 30 bed, a plurality of pipes supported upon the same and having upstanding jet nozzles, a header connecting said pipes, and regulable means for feeding a washing liquid to said header; combined with a pair of angle irons

supported by the bed above the plane of said pipes, their upright flange constituting guides for the boxes and their horizontal flanges being inturned, bearings on the latter, and cross rollers whose trunnions are 35 journalled in said bearings.

3. In a box washing apparatus comprising a frame, a series of longitudinally disposed pipes supported upon the same having upstanding jets, a gang of box receiving transversely disposed rollers mounted above the pipe jets; the combination of a fluid mixing apparatus including a fluid mixing head loop having one leg in communication with the series of pipes, a fluid delivery pipe in communication with the other leg of the mixing loop, steam and water pipes in communication with the fluid delivery pipe, a valve for the steam pipe and a valve for the water pipe, arms extending from said valves, a bracket secured to the steam pipe and water pipe, a lever carried by the bracket, a link connecting the lever and valves of the steam and water pipes, whereby they may be simultaneously actuated, and other valve control means above the last mentioned 55 valve for independently regulating the quantity of fluid passing through each of the pipes.

In testimony that I claim the foregoing I have hereunto set my hand at West Bend, in 60 the county of Washington and State of Wisconsin.

ADAM M. SPAETH.
